SHAVING BRUSH HOLDER

Myer K. Katz, New York, N. Y.

Application March 13, 1944, Serial No. 526,161

5 Claims. (Cl. 132—81)

My invention relates to a shaving brush holder and more particularly to a combination of brush holder and shaving bowl.

The principal objects of my invention are to devise a shaving brush holder that will form a part of the shaving bowl; that will support the brush with the bristles down; that will not interfere with the use of the bowl; and that will permit contact with the open atmosphere to enable the brush to dry quickly.

Other objects are to provide a holder that may be separated from the bowl, that is attached to the lid, that is readily accessible from the outside of the covered bowl, that is inexpensive to manufacture, and simple in construction.

I accomplish these and other objects and obtain my new results as will be apparent from the device described in the following specification, particularly pointed out in the claims, and illustrated in the accompanying drawing, in which:

Fig. 1 is a perspective view of one form of my combined bowl and brush holder.

Fig. 2 is a cross-sectional view illustrating the threaded connection between holder and bowl lid.

Fig. 3 is a side view of a modification with integral holder and lid.

Fig. 4 is a top view of the same.

Fig. 5 is a cross-sectional view of a wire holder detachably secured in a slot around the circumference of the lid of the shaving bowl.

Fig. 6 is a perspective view of the wire holder of Fig. 5.

Fig. 7 is a cross-sectional view of a wire holder detachably secured to a central knob forming the handle for the lid of the shaving bowl.

Fig. 8 is a perspective view of the wire holder of Fig. 7.

Referring more in detail to the drawing, and especially to Figure 1, reference numeral 10, designates a form of brush holder made of a composition shell material such as Celluloid or other plastic moulded or shaped to form a neck portion 11 having an open slot 12, a cylindrical wall section 13, provided with a longitudinal opening 14, a base section 15 to which the cylindrical wall section 13 is secured, and containing on the bottom side thereof a threaded recess 16. The shaving bowl base 17 contains the soap 18, and a lid section 19, fitted thereon, having a threaded knob 20 to which the threaded recess 16 of the brush holder may be attached.

The brush 21 is of the usual shape with handle 22 having a neck section 23, and bristles 24 extending from the handle 22.

The brush 21 is inserted into the longitudinal

opening 14 of the brush holder 10, with the neck 23 of the brush snapping into position in the neck portion of the holder, the walls of the holder being sufficiently resilient to expand under pressure and lock the brush into the position shown in Fig. 2.

In Fig. 3, the brush holder 25 is formed from a curved piece of sheet or formed material with the base end 26, secured to a curved top of the bowl lid 27, and the brush supporting end 28 slotted, as in Fig. 4, to permit the neck of the brush to be snapped therein, and supported, as shown by the dot-dash lines of Fig. 3.

In Figs. 5 and 6, the brush holder 29, is made of wire with brush supporting prongs 30, open to receive the neck of the brush.

The base 31 curved and open to snap over a circumferential slot 32 about the edge of the lid 33 of the shaving bowl 34.

In Figs. 7 and 8, a wire holder 35 provided with 20 prongs 36, and circumferential base 37 is adapted to be detachably secured to a circumferential slot 38 formed about the knob 39, part of the lid 40.

In each case the brush is supported a suitable distance above the lid, to allow the bristles to hang freely.

By the foregoing construction I have accomplished the objects of my invention. I have provided a shaving brush holder that will support the brush above the shaving bowl, which occupies a minimum amount of space in the base area, which is open to the drying effect of the atmosphere, which supports the brush with the bristles down, which permits the brush to be inserted into the bowl without interference from the holder from which it is readily detached, which enables the holder to be removed simultaneously with the lid, and permits the holder and brush to be utilized as a separate and distinct device from the shaving bowl, as is indicated in Figs. 1, 2, 5 and 6, wherein the brush and holder may be removed and used separately without being secured to the shaving bowl or lid. Any suitable material can be used to form the holder.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained, and new results accomplished, as it is obvious that the particular embodiments herein

shown and described are only some of the many that can be employed to attain these objects and accomplish these results.

What I claim and desire to secure by Letters Patent is as follows:

1. A combination of shaving brush holder and shaving bowl for making lather, having a lid therefor, said brush holder at one end thereof carried by said lid and extending above the same, and having means at the other end thereof for securing thereto and supporting in an upright position and outside the shaving bowl the handle of a shaving brush.

2. A combination of shaving brush holder and shaving bowl for making lather, having a lid therefor, said brush holder at one end thereof carried by and removably secured to said lid and extending above the same, and having means at the other end thereof for securing thereto and supporting in an upright position and outside the shaving bowl the handle of a shaving brush.

3. A combination of shaving brush holder and shaving bowl for making lather, having a lid therefor, said brush holder at one end thereof carried by and circumferentially secured to the 25

edge of said lid and extending above the same, and having means at the other end thereof for securing thereto and supporting in an upright position and outside the shaving bowl the handle of a shaving brush.

4. A combination of shaving brush holder and shaving bowl for making lather, having a lid therefor, said brush holder at one end thereof carried by and detachably secured to said lid and 10 extending above the same, and having means at the other end thereof for securing thereto and supporting in an upright position and outside the shaving bowl the handle of a shaving brush, said brush holder having a base section for supporting the shaving brush independently of said lid.

5. A combination of shaving brush holder and shaving bowl for making lather, having a lid therefor, said brush holder made of wire and having one end thereof carried by said lid and 15 extending above the same, and having means at the other end thereof for securing thereto and supporting in an upright position and outside the shaving bowl the handle of a shaving brush.

MYER K. KATZ.
